DISPOSABLE FILTER AND HOLDER

Arnold I. Troy, Scarsdale, N. Y.

Application April 28, 1950; Serial No. 158,837

9 Claims. (Cl. 131—10)

1
This invention relates to a mouthpiece for cigarettes, cigars and pipes and more particularly to a mouthpiece containing a filter element and which can also serve as a disposable holder.

Permanent or non-disposable cigarette holders have recognized disadvantages. Thus, they are unsanitary, they serve to reinfect the user and they accumulate distasteful odors and flavors.

It is an object of this invention to provide a tip for cigarettes which is separate from and attachable to a cigarette and which serves both as a disposable cigarette or cigar holder and as a filter for removing undesirable products from the smoke.

It is a further object of this invention to provide a filter in a tip which may be attached to cigarettes, cigars or pipes and which filters the smoke by cooling.

It is a still further object of this invention to provide such a tip for filtering smoke which contains a cooling element and an absorbent element.

These and other objects of this invention will become more apparent upon consideration of the following description taken together with the accompanying drawings in which:

Fig. 1 is a perspective view of the mouthpiece device of this invention assembled with a cigarette, one part of the mouthpiece being partly broken away;

Fig. 2 is an end view of the mouthpiece device of this invention showing the filter;

Fig. 3 is a sectional view of the filter element of the mouthpiece device shown in Fig. 2, taken on line 3—3 in the direction of the arrows;

Fig. 4 is a perspective view of the filter plug of the filter element enlarged and partially unwound; and

Fig. 5 is a perspective view of a modified filter plug made according to the invention, shown enlarged and partially unwound.

In general this invention provides a mouthpiece for a cigarette containing a filter composed of a metal foil having high heat conductivity and a highly absorbent paper arranged in alternate layers axially to the cigarette fitting, mouthpiece. The smoke, when drawn through the mouthpiece from the cigarette, thus passing over the filter, is cooled by the metal foil element and loses some of its more undesirable components by condensation. The condensate is in turn removed from the cool metal foil by absorption into the absorbing element.

In a preferred embodiment, as shown in Fig. 1, the invention comprises an outer sheath 10

which contains a filter 11. The filter 11 occupies a portion of the cylindrical interior of the sheath 10 and the remainder of the interior of the sheath 10 is formed by the walls and the filter 11 into a cup-like recess 12. A cigarette 13 is attached to the mouthpiece by the insertion of one end into the recess 12. The recess 12 is of sufficient depth and the diameter of the sheath 10 is proportioned so that the cigarette 13 is held securely in the mouthpiece. Thus held in the mouthpiece, the cigarette 13, when lit at the opposite end and smoked, passes its smoke out into the sheath 10 and through the filter 11. The smoke is drawn from the sheath 10 by the smoker through the end opposite the recess 12. Therefore, in smoking a cigarette through the mouthpiece of this invention, the smoke must be drawn through the filter 11 as if it were integral with and a part of the cigarette 13.

As shown in Fig. 2, the filter 11 contained in the sheath 10 is wound in a spiral coil of alternating layers of a metal element 14 and an absorbent element 15 to form a filter plug 18. The absorbent element 15 is essentially enclosed within the spiral wound element 14 in that the metal element 14 is the longer strip and completely envelopes the absorbent element 15 of the coil so that a tail 16 of the metal element 14 at the outer end of the coil overlaps the end of the absorbent element 15 and part of an inner convolution of the metal element. As shown in Fig. 3, the outermost convolution of the metal element 14 and the tail 16 are wrapped around the filter plug 18 and are in contact with the inner wall of the sheath 10 and make a good heat transmission contact therewith. On the other hand, the absorbent element 15 is wound on itself at the center of the filter 11 to provide a core 17 within the inner convolution of the metal element 14.

In Fig. 3, the section of the sheath 10 and the filter 11 shows the axial alignment of the layers from each convolution of the metal element 14 and the absorbent element 15. The core 17 in the vicinity of the center of the sheath is shown and the contiguity between the inner wall and the sheath 10 and the outer convolution of the element 14 is shown. As shown in Figs. 1—3, the filter plug 18 is a separate part insertable into and removable from the sheath 10. In a modification of this invention, the filter plug 18 may be incorporated in the tip end of a cigarette to effect the same inventive results as in the embodiment shown in the drawings.

In operation, this invention is employed to remove from the smoke of a cigarette those irriti-

tating and noxious components which are considered undesirable to the smoker. At the same time, the smoke is cooled so as to remove some of its heat, and therefore bitterness to the taste of the smoker. The impurities are removed by the cooling effect applied to the smoke as it passes through the filter. This cooling is performed by the metal foil over which the cigarette smoke passes. The spiral metal element 14 in turn is cooled by the conduction of the heat through the wall of the sheath 10 to the ambient atmosphere. As the cooling of the smoke lowers its temperature appreciably, some of the impurities in the smoke have their temperatures lowered below the condensation point and they condense onto the surfaces of the metal foil convolutions. The thus condensed impurities present on the metal foil in the liquid state are removed therefrom by absorption in the adjacent absorbent element 15 which is wound with the metal element 14. This absorption tends to add to the cooling of the metal element 14 and thus prepare for an additional charge of smoke from the cigarette 13. The removal of the condensate from the metal foil surfaces also clears those surfaces to receive additional condensate from subsequent passages of cigarette smoke.

The metal element 14 may be formed of any metal which has the ability to absorb and conduct and dissipate heat rapidly and is also sufficiently ductile to be formed into a thin continuous strip of foil. Aluminum is preferred for this purpose. Copper, silver, gold and magnesium are also suitable conductors and could be used for this purpose. The effectiveness of the filter can be varied by variations in the axial length of the filter. The longer the filter is, the better will be its filtering properties and its cooling effect. As shown in Figs. 1 through 4, the metal foil element 14 is shown as a smooth or flat strip and the absorbent element 15 is shown as a crinkled or corrugated strip. However, in Fig. 5 the metal foil element 14a is shown as crinkled, corrugated or undulated while the absorbent element 15a is shown as a smooth or flat strip. Any form of the unsmooth surfaced element will provide the device of this invention when assembled according to this invention. The important feature of the unsmooth surfaced element is that there be provided thereon a series of alternate grooves and ridges. Also, while the elements 14 and 15 have been shown assembled as a pair of juxtaposed layers wound involutely on themselves, the filter may also be made up of cylinders alternately of metal foil and absorbent material. These cylinders being arranged axially with the sheath 10.

The advantages of the mouthpiece device of this invention include among others a relatively small tip to be attached to or incorporated in a cigarette which has the effectiveness in cooling and removing impurities that a much longer and more cumbersome filter would have. The components of the filter element of this mouthpiece device are relatively inexpensive and easy to assemble. In addition, the relatively low cost of this mouthpiece makes it disposable with each cigarette and therefore more convenient.

The above described embodiments will be understood as merely illustrative. Various other modifications may be made of the invention, for example, the filter of this invention might be adapted for cigars and for use in the stems of pipes.

A modification of this invention may provide

the metal foil with convolutions in and near the center which have dull surfaces, and convolutions at or near the periphery which have brightened surfaces. This modification employs a physical principle of the absorption and radiation of heat to assist in achieving the object of this invention. A given dull surface absorbs heat more rapidly than a similar bright surface. A bright surface will reflect heat. In the cylindrical cigarette filter which is the preferred embodiment of this invention, the center convolutions will receive the greatest quantity of smoke. Dulling these convolutions will make them more effective in absorbing heat from the smoke. The outermost convolutions if they are made bright will not absorb as much heat. This differential between the dull inner convolutions and the bright outer convolutions will set up a flow of heat outward to the radiating periphery represented, in part, by the tail 16. The heat transferred from within the metal foil element 14 will finally be dissipated to the atmosphere through the mediation of the plug 18. A further modification of this invention may be had in providing a filter plug made up of convolutions of metal foil alone. It will be readily understood that other modifications may be made of the above described invention without departing from the spirit thereof. It is therefore intended that this invention be limited by the scope of the appended claims.

I claim:

1. In a smoke filter for the heated gases produced upon combustion of tobacco in smoking articles, the combination of a continuous strip of imperforate metal foil wound into a convolute coil, an imperforate strip of absorbent material juxtaposed and interpositioned with said convolute continuous strip of metal foil and convolutely wound to provide with said convolute strip of metal foil alternate layers of metal foil and absorbent material, surfaces of said convolute metal foil and surfaces of said convolute absorbent material being spaced from each other to provide a large number of continuous passages substantially parallel to the axis of the coil through said smoke filter between said juxtaposed alternate layers of foil and absorbent material, each passage being of small transverse cross section whereby the condensation from said heated gases on said surfaces of said metal foil is absorbed by said juxtaposed surfaces of said absorbent material and said small passages are maintained substantially free from said condensation products.

2. In a combined holder and smoke filter for treating the heated gases produced upon combustion of tobacco in smoking articles, the combination of an outer cylindrical casing containing a thin continuous strip of imperforate metal foil convolutely wound, an imperforate strip of absorbent material juxtaposed and interpositioned on the said convolute continuous strip of metal foil and convolutely wound to provide with said convolute strip of metal foil alternate layers of metal foil and absorbent material, said coils being positioned in said cylindrical casing to axially receive said heated gases from a smoking article inserted in one end of said cylindrical casing, surfaces of said convolute absorbent material being spaced from said foil surfaces to provide a large number of small continuous passages so as to receive said heated gases, whereby the condensation from said heated gases on said surfaces of said metal foil is absorbed by said

juxtaposed surfaces of said absorbent material and said small passages are maintained substantially free from said condensation products.

3. In a smoke filter for a smoking article a laminated sheet of material comprising alternate layers of metal foil and absorbent sheet material, said laminated sheet being shaped into convolute form, said absorbent sheet material being crinkled to provide a plurality of continuous passages and a sleeve of sheet material encompassing said laminated convolute sheet.

4. A smoke filter as claimed in claim 3, wherein the metal foil is crinkled.

5. A smoke filter as claimed in claim 3, wherein the sleeve is of greater length than the coil and is adapted to receive a smoking article therein.

6. A smoke filter as claimed in claim 3, wherein the metal foil is formed with alternate ridges and grooves.

7. A smoke filter as claimed in claim 1, wherein the centrally located portion of the coil has dull surfaces and the outer portions of the coil have bright surfaces.

8. A filter for a smoking article comprising a coiled laminated structure consisting of superposed sheets, each sheet being of a different material, the materials being in alternate overlapping relationship, said materials being a sheet of metal foil and a sheet of cellulosic material, the cellulosic material having the characteristic of absorbing the liquids and retarding the passage of solvents and the metal foil material having the characteristic of causing the condensation of gases that contact the foil surface as the gases pass through the laminated structure, the said
